CLAIM

I claim the ornamental design for a tall shower caddy, as shown and described.

DESCRIPTION

FIG. 1 is a front perspective view of the tall shower caddy of the present invention.

FIG. 2 is a rear perspective view of the tall shower caddy of FIG. 1.

FIG. 3 is a front elevation view of the tall shower caddy of FIG. 1.

FIG. 4 is a rear elevation view of the tall shower caddy of FIG. 1.

FIG. 5 is a side elevation view of the right side of the tall shower caddy of FIG. 1.

FIG. 6 is a side elevation view of the left side of the tall shower caddy of FIG. 1.

FIG. 7 is a top plan view of the tall shower caddy of FIG. 1; and,

FIG. 8 is a bottom plan view of the tall shower caddy of FIG. 1.

In the drawings, the broken lines depict portions of the tall shower caddy that form no part of the claimed design. The tall shower caddy is shown with a symbolic break in its length, illustrated by dashed lines in FIGS. 1-6. The appearance of any portion of the article between the break lines forms no part of the claimed design.
